METHOD FOR MANUFACTURING GASES

Hiram J. Carson, Cedar Rapids, Iowa

Application October 31, 1930, Serial No. 492,457

5 Claims. (Cl. 48—204)

This invention relates to the production of combustible gas including blue and/or carburetted water gas and/or gases having a high hydrogen content, and the production of hydrogen from hydrocarbons including methane and/or natural gas and/or butane or propane in blue and carburetted water gas sets, the principal objects of the invention being to effect economies in such production by improvements in the methods employed.

This invention, which embodies improvements upon and is a continuation in part of the inventions described and claimed in my co-pending applications 199,572, filed June 17, 1927, and 15 353,576, filed April 28, 1929, comprehends:

Improved methods of: furnishing preheated air for blasting; generating and superheating steam for gas making; air blasting a generator fuel bed; admitting steam to a generator fuel bed; removing of ash and clinker forming material from a water gas generator in liquid form; introducing fluxing material into a generator fuel bed; gasifying bituminous fuel in a water gas generator; recovering liquid hydrocarbons and ammonia 20 from bituminous fuel; introducing and gasifying liquid hydrocarbons in a carbureting chamber; superheating and/or decomposing methane and/or natural and/or other gases for producing 25 of hydrogen; the production of gases high in hydrogen content from non-volatile and/or bituminous fuel and/or hydrocarbons including butane and propane; and the manufacture of carburetted water gas having a relatively high heating value.

As is well known, in the usual operation of water gas sets, the time is roughly divided into two periods; the blasting or heating up period, and the running or gas making period. The heat developed during the air blasting period and 35 stored in the generator fuel bed, is available in the gas making period for decomposing the steam admitted to the generator. In the usual operation of carburetted water gas sets the potential and sensible heat in the blow gases leaving the 40 generator is used to store heat in regenerative chambers known as carbureting and gas superheating chambers, the heat so stored being used for vaporizing and cracking liquid hydrocarbons and fixing the resulting hydrocarbon gases during the gas making period.

The air for blasting usually enters the generator at about atmospheric temperature and the steam for gas making usually enters the generator with a relatively small amount of superheat, 45 if any, and often containing moisture. The air

must be heated in the generator to ignition temperature before combustion takes place and any moisture in the steam must be vaporized, and the steam heated to a reaction temperature of over 1800° F. or more for steam decomposition before water gas is formed in any appreciable amount. The blow gases, from air blasting, leave the apparatus while containing a substantial amount of sensible heat in addition to the potential heat in any combustible gases therein.

In practice, at the beginning of a running period, the decomposition of steam is rapid and nearly complete for a short period, but falls off rapidly thereafter, owing to the lower rate of decomposition as the generator fuel bed temperature falls.

Very little steam is decomposed at temperatures below 1832° F. whereas the rate of decomposition is estimated to double with every rise of 180° F. in temperature above that point and such decomposition is very rapid at temperatures of 2192° F. and higher. While the temperatures in the steam decomposition zone in a generator fuel bed may vary at different levels in that zone, the minimum practical temperature of its highest 20 temperature portion, which should be of sufficient thickness to give the steam enough time of contact with the hot fuel to form blue water gas in practicable amounts, is about 1832° F. and the heat in the fuel bed useful for steam decomposition 25 is the heat stored above that temperature.

Heretofore, insufficient account has been taken of the foregoing facts. Steam admitted to the generator is actively decomposed at first, but decomposition is soon arrested as the fuel temperature is lowered by the cooling action of such steam decomposition. As the temperature drops, less and less of the steam admitted is decomposed, and the resulting increasing excess of undecomposed steam has the harmful effect of further 30 cooling the fuel bed with no useful result.

To restore heat storage to the fuel bed at proper temperature levels after such cooling: fuel, air, and time are necessary, and as the fuel bed must be heated first to the temperature where steam 45 decomposition begins at an effective rate and as the useful heat storage is that above about 1832° F. the blasting and heating to bring the fuel temperature in the steam decomposing zone up to 1832° F. may be avoided by keeping the mean 50 temperature of the fuel in that zone at or well above 1832° F.

Where steam without superheat and air without preheat is delivered to the generator, heat stored in the fuel bed must be used to superheat 55

the steam to decomposition temperatures and preheat the air to ignition and combustion temperatures.

In decomposing steam the reaction heat must be supplied at high temperature levels and once heat is stored in a generator fuel bed above say 1800 or 2000° F. it is a wasteful procedure to use the heat at these high levels for a relatively low temperature operation such as superheating steam up to the reaction temperature and preheating air.

This invention contemplates the use of otherwise waste heat in the combustible gases and blast gases to superheat the steam and preheat the air to the generator, thereby conserving the heat stored and generated therein at high temperature levels for the directly useful purpose of steam decomposition and gas formation, and permitting operation at higher average temperatures in the generator.

In air blasting a generator fuel bed it is well known that more and more carbon monoxide is produced for a given rate of blasting as the temperature of the fuel rises and the high temperature zone in the fuel increases in thickness.

It is also well known that the percentage of carbon monoxide in blow gases may be limited by increasing the rate of blasting, thus reducing the time of contact of the burned gases with the hot fuel.

In the usual method of air blasting water gas sets the air is blown into the bottom of the generator through grates and the entire fuel bed to the blow gas offtake. The carbon monoxide content of the blow gases is limited by shortening the air blasting and gas making periods as much as practicable and air blasting at the highest practicable rate. Less heat is stored in the fuel in the shorter blasting period and less is needed for the short gas making period, and less carbon monoxide is produced in the blow gases.

Optimum conditions for the decomposition of steam and run gas formation require the longest practicable time of contact of the steam with the fuel at the highest practicable temperature. A thick high temperature fuel bed is desired.

This invention contemplates the maintenance of the CO content of the blow gases within the desired limits and the building up of a steam decomposition zone of greater thickness and maintained at a higher temperature than is practicable in the usual methods of operation now used.

This invention contemplates the introduction of air to the fuel bed at different levels separately controllable at each level so as to limit the time of contact of the burned gases with the high temperature fuel resulting from combustion at each level.

Air may be introduced first at the lower level furthest from the blow gas offtake, then discontinued as a high temperature zone is built up near that level. Air may then be introduced at the next higher level so as to by-pass the hot layer of fuel resulting from blasting at the first level, then discontinued at the second level, and commenced at the third level and so on until a high temperature fuel bed of the desired thickness is built up.

This invention accordingly contemplates the admission of air at one level at a time or at different levels simultaneously. When air is continuously admitted at one level the carbon monoxide in the resultant gases may be burned by air simultaneously admitted at another level

thus decreasing the carbon monoxide content of the blow gases.

The rate of air blasting is limited by the point at which excessive amounts of fuel are blown out of the generator. In present operation with the air for blasting admitted under the generator grates and the fuel column not uniformly porous, the air seeks the path of least resistance through the fuel and channeling results with overheating of some portions of the fuel bed and little heating of other portions. As a result a substantial part of the fuel bed is relatively inactive.

This invention contemplates that air for blasting will be supplied to the generator at relatively high velocities through a plurality of tuyères in the generator at different levels as desired thus insuring a relatively uniform air supply to, and penetration of, the generator fuel bed.

In present operation the steam for gas making follows the path of least resistance through the fuel bed and often with a channeling effect.

This invention contemplates the admission of steam to the generator at relatively high velocities through tuyères in the generator at different levels as desired, thus insuring the admission of steam uniformly to the different points of the fuel bed.

In present operation the steam and air enter the base of the generator relatively cold and chill the bottom zone of the fuel bed. Down steam runs are necessary from time to time to drive the heat down toward the grate as otherwise the cold zone would gradually move upwardly.

This invention contemplates that with steam superheated above the ignition temperature of the fuel and/or admitted above the bottom zone and with or without preheated air, the bottom zone of fuel is kept sufficiently hot so only up steam runs need be made.

This invention also contemplates the making of down steam runs and a combination of up and down steam runs and a practically complete recovery of all the otherwise waste heat in the usual water gas process as well as reducing the number of or avoiding the use of valves in hot locations.

In present practice, gas making is continued until the accumulation of ash and clinker in the lower portion of the generator fuel bed prevents further operation in a practicable manner. Gas making is then discontinued, to permit the removal of ash and clinker, after which operations may be resumed. This invention contemplates the easy removal of ash and clinker in the form of molten slag so as to permit continuous or nearly continuous operation with a uniformly clean fuel bed and without the arduous labor and loss of time usual in present operation or the use and maintenance of costly mechanical grates for continuous ash and clinker removal.

This invention further contemplates that air and steam may be admitted selectively as desired and gas drawn off so the liquid slag formed in the bottom zone of the generator fuel column will not be substantially exposed to the cooling action of the entering steam, will remain hot during the period of steam admission, thus permitting ready ignition at the beginning of the blasting period and keeping the slag substantially at and above the melting point.

This invention also contemplates the use of metallic ore as iron ore as a fluxing material and the drawing off of molten metal as well as liquid slag.

This invention also contemplates the use of

steam superheated near to or above the fusing temperature of the ash as desired which reduces or avoids any chilling action on the slag; the continuous and quick removal of the slag from the generator bottom to avoid any undue freezing thereon and consequent interruptions to operation.

The use of preheated air for blasting facilitates the slagging operation. A flux may be charged 10 with the fuel or introduced in the bottom zone of the fuel bed or blown in admixed with the blasting air as needed and desired. In the latter case the flux may be immediately used in liquifying the slag and the time interval required for 15 fluxing material charged with the fuel to work down to the slagging level is avoided.

This invention contemplates the introduction of a fluxing material in the bottom zone of the fuel bed when desired, also the introduction of 20 combustible gas with the blasting air in the bottom zone in case of difficulty in slagging which may, for example, be occasioned by a deficiency of combustible in the fuel at the slagging level. The blasting air may also be enriched with oxygen 25 for further hastening combustion and liquifying the slag. A limited amount of air and/or oxygen may be admitted at the lower level during the gas making period to keep the slag liquified.

30 When bituminous fuel is used in a generator of the usual type having the blue and blow gas off-takes at the same level, volatile matter from the fuel is driven off during the gas making period and also during the air blasting period. Also, in the usual up and down run method of operation in which steam for gas making is alternately admitted above and below the fuel bed, the hydrocarbons distilled from the fuel during the down run portion are passed through the hot 35 zone of the generator fuel bed and broken down into mostly carbon and hydrogen.

With bituminous fuel, such as coal, used as generator fuel, the invention contemplates the use of an upper carbonizing zone and a lower incandescent or generating zone. The air blast gases from the lower zone, with or without the secondary combustion thereof, may be used for externally heating the upper zone or a portion of such blast gases may, when desired, be passed through the upper carbonizing zone for internally heating the fuel therein. Part or all of the hot blue water gas from the lower incandescent zone may be passed through the fuel in the upper zone for devolatilizing the fuel and any remaining portion of the blue 40 gas drawn off separately as for enrichment with liquid hydrocarbons. With fuel containing little or no volatile matter, such as coke, the invention contemplates passing part or all of the blue water gas from the lower zone through the newly charged fuel in the upper zone to thereby preheat such fuel before it descends into the lower water 45 gas generating zone.

This invention also provides for a carbonizing zone above the generating zone with the heat in the blue gas and/or superheated steam admixed with air or oxygen when desired and utilized in internally heating and carbonizing the fuel.

In carbonizing fuel in water gas generators by internal and/or external heating, as above described, difficulties are experienced with some fuels which on heating swell, arch or hang in generators and form a plastic zone through which gases are passed with difficulty, if at all.

The volatile matter of bituminous fuels is of 75 varying composition and distillable at different

temperatures. The volume and quality of the volatile matter given off varies with the temperature and time of heating.

When the volatile matter distilled off at relatively higher temperatures passes through cooler fuel, some or all of it is usually condensed on the cooler fuel. This condensate encases the lumps or particles of fuel in a liquid envelope often of a plastic nature which is not again vaporized until the fuel passes into a zone of higher temperature. Meanwhile the coal lumps and particles contain volatile matter distillable at relatively low temperatures, which being partially or wholly confined within the liquid envelope, causes the fuel to swell.

If the volatile matter evolved from bituminous fuel as it is heated is removed from contact therewith substantially as it is formed under temperature and partial pressure conditions above the condensation point, the time required for distilling off the volatile matter at any given temperature is greatly reduced; cracking of the hydrocarbons so evolved is avoided and the condensable portion of these hydrocarbons may be recovered in liquid form. With the hydrocarbons drawn off as formed and cracking avoided, the heat required for carbonization is substantially less.

If swelling or sticking coals are preheated for a time at 900° F. more or less, the swelling properties and tendency toward the formation of a plastic zone is thereby reduced.

This invention contemplates when desired the devolatilization of the fuel by the heat in the blue gas and any undecomposed steam mixed therewith passing through it at relatively higher temperatures than are obtained in usual practice and supplemented by other methods more fully hereinafter described.

This invention also contemplates preheating the coal to prevent sticking and the formation of a plastic zone and the distillation of the fuel under controllable temperature conditions to permit the evolving and recovery of condensable hydrocarbons of varying qualities as desired as hereinafter more fully described.

The invention also contemplates the distilling of the newly charged bituminous fuel and production of gas high in hydrogen content with steam preferably highly superheated, passing downwardly through it and thence with the hydrocarbons distilled from the fuel on downwardly through incandescent fuel to thereby crack the hydrocarbons mostly into hydrogen and carbon and/or water gas from the steam and the carbon thereby liberated and/or the carbon from the fuel.

This invention further contemplates the production of a high hydrogen content gas as by liquid hydrocarbons sprayed in the upper part of the generator in a downward current of highly superheated steam with the mixture passed downwardly through the incandescent fuel.

In the manufacture of carburetted water gas from bituminous fuel, the invention contemplates passing a part of the water gas through the carbonizing chamber and the remaining portion in desired volume through a carburettion chamber for enrichment therein by hydrocarbon vapors from liquid hydrocarbons.

With coke used as fuel the proportions of water gas drawn off separately, passed through newly charged fuel and through the carburettor or through regenerators for superheating steam and any air or oxygen admixed therewith may be varied as desired and as hereinafter described.

The invention also contemplates the admission of steam in the lower zone of the carbonizing chamber for the formation of ammonia and/or blue gas with such formation furthered, when desired, by the presence of lime or limestone when charged with the fuel for the additional purpose of fluxing the ash; the maintenance of optimum temperatures for ammonia formation in the carbonizing chamber when ammonia recovery is desired and the formation of methane in relatively large volume because of the catalytic effect in such production by any lime or limestone charged with the fuel as a fluxing agent for the ash.

In the manufacture of carburetted water gas it is well known that optimum conditions for the gasification or cracking of liquid hydrocarbons in the carburetter require the maintenance of temperatures within fairly narrow limits. It is also well known that in present operation the temperatures in the carburetter fluctuate widely, with a fairly rapid deterioration of the heat absorbing material, usually fire brick, because of the thermal shock incident to the temperature fluctuations. The temperatures in the top courses of checker brick have been found to fluctuate from an average minimum of 640° F. to an average maximum of 1886° F. with extreme mean variations from 513° F. to 2000° F. Shut downs and replacements of checker brick are frequently necessary. At the higher temperatures the hydrocarbons are over-cracked with a deposit of carbon and the formation of objectionable compounds such as naphthalene and, at the lower temperatures, the hydrocarbons are not completely cracked or utilized and other objectionable compounds such as indene and styrene are formed.

The brick in the carburetter are rapidly cooled by the vaporization and cracking of the hydrocarbons and in the usual up and down run methods of operation, of carburetted water gas sets are further cooled by the relatively cool blue gas and undecomposed steam which enter the carburetter at temperatures substantially lower than required for optimum hydrocarbon cracking conditions. This cooling often progresses to such an extent that it is difficult to ignite the blow gases and secondary air during the following air blasting period.

The invention contemplates the use of a combustion and heat absorbing chamber between the generating and carburetting chambers in which heat may be stored during the blasting period for preheating the blue gas and undecomposed steam toward and above the optimum temperatures for the gasification of the hydrocarbons before such blue gas and undecomposed steam enter the hydrocarbon admission zone.

During the gas making period the water gas and undecomposed steam are heated to relatively high temperatures in passing through the heat absorbing chamber and in entering the hydrocarbon gasification zone carry heat to the hydrocarbon particles in this chamber with more nearly uniform and optimum temperatures prevailing in the gasification zone.

This invention also contemplates drawing off the blue gas from the generator at a sufficiently high temperature for furnishing the heat for cracking and gasifying the hydrocarbons within the desired temperature limits and the use of a mixing chamber in the hydrocarbon admission zone in the carburetter to allow for the mixing therein of the highly heated entering blue gas and steam with the hydrocarbon mist or particles directed into and against the descending gas

stream. The mixture of this entering hot gas and steam with the heat radiated to these particles from the carburetter lining and adjacent refractory material bring the hydrocarbon particles to or nearly to optimum temperatures for cracking. In the presence of a reactive gas such as hydrogen in the blue gas at optimum cracking temperatures, stable hydrocarbon gases are formed and a practically complete conversion of the carbon and hydrogen in the hydrocarbons into such gases is effected.

A uniform or nearly uniform descent of the mixture of hydrocarbon particles or gas and blue gas and steam from the generator will take place in the hydrocarbon admission zone, for the hot gas and steam after passing through the supplementary heat absorbing chamber and in striking the hydrocarbon particles, cool and drop out of the way of the hydrocarbons and gas and steam introduced thereafter, with the uniform descent of the mixed gas column in the chamber. The amount of secondary combustion and heat storage in the heat absorbing zone may be so regulated that the blue gas and steam will be heated to the required temperature in conjunction with heat radiated to the hydrocarbon mist and blue gas-hydrocarbon mixture from adjacent refractory surfaces for producing optimum temperature conditions for hydrocarbon cracking when cooled by and mixed with the hydrocarbon particles.

The mixture of blue gas and hydrocarbon gas and steam and any hydrocarbon mist therein may, when desired, then be passed through heat absorbing material, such as checker brick, which have not been exposed to the flames of the secondary combustion of the blow gases and have temperatures substantially within the optimum temperature range for hydrocarbon gasification so that the hydrocarbon mist is then cracked therein.

The relatively large volume of blue gas entering the carburetter provides low partial pressure conditions for the hydrocarbon vapors which furthers the conversion of liquid hydrocarbons into stable hydrocarbon gases. Reduced absolute pressures further favor the conversion of the liquid hydrocarbon into stable hydrocarbon gases. When it is desired to reduce the absolute pressures, the carburetter gas outlet is equipped with a vacuum pump which may be sufficiently large to handle all blue and hydrocarbon gases. The pump in such case is preferably arranged to draw the gases through a condenser so as to reduce the gas volume and the size of pump required. Any outlet from the generator other than the carburetter outlet may also be provided with a vacuum pump and condenser.

The relative proportions of gas drawn off through each offtake may be regulated by the size and speed of each pump.

The volume of gas withdrawn through each outlet may also be regulated by dispensing with the pump in the second gas outlet and providing a valve in the passageway between the generator and carburetter which may be partly closed during the gas making period to restrict the flow of gas to the carburetter as desired and to permit higher pressures in the generator and the discharge of gas through the second outlet at pressures higher than the reduced pressures in the carburetter.

With the hydrocarbons as butane or propane used for enrichment, the invention contemplates the cracking or conversion of these in the manner previously described into lighter hydrocarbons of

the desired density and heating value at temperatures below those at which naphthalene is formed and above those temperatures at which indene and styrene are formed.

5 When it is desired to produce a gas high in hydrogen from methane and/or natural gas, the invention contemplates the use of methane or natural gas with steam in the foregoing.

The invention contemplates a process wherein 10 regenerative chambers are utilized in which heat from the blow and/or run gases is stored and used for superheating and/or generating steam and preheating air, and so designed that the blast gases pass downwardly and the steam and air pass upwardly through the heat absorbing material in these chambers. A practically complete utilization of the capacity of these chambers is thereby effected.

The decomposition of methane and/or natural 20 gas and like hydrocarbons into carbon and hydrogen in practicable amounts requires an appreciable time of contact at high temperatures. The superheating of the methane and/or natural gas and building up of a thick high temperature zone 25 in the fuel bed by air blasting as previously described provides optimum conditions for the production of hydrogen from these gases.

The methane, natural or other gas such as refinery gas is admitted to regenerators heated as 30 previously described for steam in water gas production, the air blasting methods being the same as previously described, and after being superheated in such regenerators is passed to and through an incandescent fuel bed in the generator where the carbon is mostly deposited, and the hydrogen and any gases admixed therewith is drawn off as described for water gas.

In the preceding, I have outlined briefly certain features and disadvantages of water gas 40 generation as heretofore commonly practiced and the objects of the present invention.

Other objects of my invention will more clearly appear from the description and claims herein-after following.

45 In the drawing forming a part of this specification, I have illustrated suitable apparatus, with certain indicated modifications under different conditions, which may be employed in the practical carrying out of my improvements in water gas generation. In said drawing—

Fig. 1 shows a carburetted water gas plant partly in elevation and partly in vertical section, suitable for carrying out my improvements and in which the operation may be varied and different parts omitted when desired.

Fig. 2 is a fragmentary section in elevation showing a modified form of the upper portion of the generator in Fig. 1.

Fig. 3 is a fragmentary section in elevation 60 showing a modified form of the lower part of the generator in Fig. 1.

Fig. 4 is a fragmentary section in elevation showing another modified form of the lower part of the generator in Fig. 1.

65 The apparatus shown in Fig. 1 is adapted for the manufacture of carburetted or-blue water gas from bituminous fuel or non-volatile fuel, such as coke, with combination up and down runs or for up steam runs only, or for down steam runs only, the arrangement being designed for increasing the hydrogen content of these gases, and for cracking methane and/or natural or other hydrocarbon gases as herein described.

The apparatus will first be described for combination up and down steam runs for the manu-

facture of carburetted water gas from bituminous fuel.

In Fig. 1 a gas generator 10 is shown communicating with a carburettor 11 which communicates with a regenerative chamber 12. The 5 chamber 12 is a steam superheater in which heat from the blast gases is stored for superheating steam.

The steam superheater 12 communicates with an air preheating chamber 14 here shown as a 10 recuperator which may be of the double regenerator type when desired in which the air for blasting is preheated by the hot products of combustion simultaneously passing through it.

A regenerative chamber is also shown at 15 15 which is adapted mainly for superheating and/or generating the uprun steam by the sensible heat in the downrun gas, and also for carburetting the down-run gas when desired.

A condenser or waste heat boiler is indicated 20 at 16 through which combustible gas from carburettor 11 may be drawn off and cooled before entering a vacuum pump as 17, or passed to such other apparatus as desired.

A blower for supplying the blasting air through 25 inlet 54 to the preheater 14 or through by-pass 53 to air header 56 is indicated at 18. A seal separator through which the down-run gas may be withdrawn from chamber 15 is indicated at 19. When desired the connection 19' may communicate with a condenser or waste heat boiler and/or vacuum pump in the same manner as 30 16 and 17 are connected to chamber 11.

As described hereinafter the regenerator 15 is used when down steam runs or combination up 35 and down steam runs are made and is dispensed with when up steam runs only are made.

The generator 10 is shown in section having mainly two zones, the lower zone 20 being the water gas generating zone and containing mainly 40 incandescent fuel. The upper zone contains a carbonizing chamber 21 which is charged with fuel, such as bituminous coal, and an ash fluxing material, such as limestone when desired, through any suitable charging device as 22. Air blast 45 inlet means are provided at different levels as at 23, 23a, 23b, and 23c. Steam inlet means are shown at 24 or 24a, 24b, 24c, 24d, or at 30 as desired and hereinafter described.

The carbonizing chamber is shown with an 50 annular passage around it for the passage of air blast gases from the lower zone to an offtake 37.

The carbonizing chamber, when bituminous fuel such as coal is used, preferably contains an assembly 33 made of a series of cylinder or cone 55 units of any desired form with the bottom end of each unit projecting over and below the top of the next lower cylinder to prevent fuel falling therein and to provide openings for the upward escape of volatile matter from the fuel into the 60 open passage through the units as will be understood.

A cap 34 is adjustable as by a cable 35 to regulate the division of flow of gases through the assembly and fuel.

65 A valved offtake 36 is shown leading from the carbonizing chamber.

The generator is shown having a hearth 31, preferably sloping to facilitate the drawing off of liquid slag as through discharge pipe 32. A 70 flux feed opening, closable in any suitable manner, is indicated at 76.

Down run gas leaves the generator through either of two passages, as indicated at 28 which is located above the hearth or through 30 at the 75

level of the hearth. One or the other of these passages is dispensed with as desired. When the down run gas offtake passage is also used for admitting steam to the generator the valve as 5 28' or 30' may be dispensed with but a valve is used when steam is forced through tuyères to generator as at level 24.

The hot down-run gas stores heat in the regenerator 15, and in its passage therethrough 10 may be carburetted by hydrocarbons admitted as at 10 with the resultant carburetted gas drawn off as through offtake 19' and seal separator 19.

The stack 74, closable by a stack valve 75, is an outlet for any air blast gases used for heating 15 the regenerator which may be burned therein by air admitted at 73.

The heat stored in the regenerator 15 during the down steam run in the generator is used for superheating up run steam admitted as through 20 71 and any air admixed therewith admitted as through 72 when combination up and down runs are used.

Water and/or works effluent may be sprayed into the regenerator as at 70 and vaporized in 25 the rising column of superheated steam from that admitted at 71 and superheated before admission to the generator when the cycle of operation provides sufficient heat in the regenerator therefor. In like manner water and/or works 30 effluent may be sprayed into the regenerator 12, as at 69 and vaporized in the rising column of superheated steam from steam admitted at 65 and the steam so generated and/or superheated is superheated further in passing through the 35 regenerative portion 49.

The pipe 29 with valve 29' is used for admitting superheated steam and any air admixed therewith from the regenerator 15 to the carbonizing chamber at 24b to blanket out the air blast 40 gases during the air blasting period when desired and to act as a vehicle and a heating agent for removing distillation vapors and gases given off meanwhile.

The valve 37' in the passageway 37 to the carburetter may be dispensed with as hereinafter described.

The carburetter 11 has a combustion chamber 38 for burning air blast gases from the generator by air admitted through 39 to heat the heat absorbing material 40 to a relatively high temperature. The usual point of admission of hydrocarbons is indicated at 42 but the invention contemplates the introduction of hydrocarbons after the zone of highly heated material as in 43 55 where the hydrocarbons are injected into and against the descending gas stream through the horizontally disposed inlets 44, as shown in Figure 1. Heat absorbing material as 41 of suitable size may also be provided when desired to vaporize and/or crack any uncracked hydrocarbons in the gases passing therethrough.

In making carburetted water gas with combination up and down runs, the steam superheating chamber 12 may be dispensed with and the 65 air preheater 14 and passageway 50 connected directly to the blow gas outlet passage 45 of the carburetter.

Under such condition, the blow gases, after 70 passing through zone 41 enter space 61, pass through opening 62 into passage 45 thence through passage 50, air preheater 14, stack 51 and valve 52 to the atmosphere, the air for blasting simultaneously passing through 14 and being preheated thereby.

75 The up run gas in passing through the pre-

heating chamber 40 is highly heated thereby and carries heat for cracking the hydrocarbons introduced at 44. The carburetted gas then passes on through the chamber 41 into the checker-work 41a and stores heat therein and is withdrawn through 57 and 58.

When desired the regenerative portion 41a 10 may be in a separate chamber with a suitable passage to it from 57, as for example, being installed in offtake 58.

The down run steam and any air admixed therewith is admitted through 65' and 66' respectively and passing through 41a is superheated by the heat previously stored therein by the outgoing carburetted gas as above described, and in 15 passing thence through 41 and 40 is progressively more highly superheated before passing to the generator.

When the regenerative portion 41a is omitted 20 the steam and any air admixed therewith may be admitted in the passage 45 as at 65'' and 66'' with the portion 41 when used and passage 45 extended downwardly to space 57.

The operation for making carburetted water 25 gas with up and down steam runs is carried on as follows:

With valve 37' open and chamber 12 and valve 48' omitted and carburetter outlet 46 connected into air preheater inlet 50 and stack valve 52 open and all other valves closed, a fire is kindled on the hearth 31 and the generator charged with fuel, preferably coke, through charging door 22. Air is admitted from supply pump 18; through 54 and 14; thence through 55, 56; lines 25 and then through tuyères 23' to the generator at level 23. 35 As blasting is continued at this level and the fuel adjacent thereto is heated to a high temperature, the carbon monoxide content of the combustion gases increases and is burned in combustion chamber 38 of the carburetter by air admitted 40 through 39. The heat absorbing material 40 is heated to a high temperature and the gases passing through 41 heat it also and pass thence through 61 and 62 and passageways 45, 46, and 50 to the air preheater 14, preheating the blasting 45 air simultaneously passing therethrough and thence out through stack 51 and stack valve 52.

As the carburetter is heated to the desired temperature and carbon monoxide in the blow gases increases in volume, air is admitted at a higher 50 level as 23a, to burn part or all of the carbon monoxide so produced, with the admission of air at 39 continued in sufficient volume to burn any remaining carbon monoxide in the blow gases.

Also as the fuel adjacent to level 23a becomes 55 so hot that carbon monoxide is produced in greater volume than desired, air blasting is discontinued at level 23a and resumed at level 23b until a fuel bed of the desired temperature and thickness is built up and the carburetter is heated 60 to the required temperature.

In air blasting the fuel bed, air may be admitted as before, first at level 23, and then discontinued as the fuel adjacent thereto becomes sufficiently hot, and resumed and discontinued 65 at level 23a in like manner, also at level 23b until the fuel is sufficiently hot. It is, however, preferable to continuously air blast the fuel at the lowest level thereby making the lowest section of fuel a carbon monoxide generator and then burning the carbon monoxide so produced by air admitted at higher levels as before described, thereby heating the fuel to high temperatures at different levels and reducing the fuel to ash 70 mostly in the lower section.

The lower portion of the fuel bed during blasting becomes intensely hot and any ash or clinker forming material therein is liquified.

Air may also be admitted at 23c at or near the top of the fuel in the generating zone 20 to burn the blow gases and give additional external heat for the chamber 21.

Also during the heating up period, a portion or all of the blast gases for part of the period may be taken through regenerator 15 to heat the same when desired, through passageway 30 or 24a, 24a', 28, whichever is used, and burned in regenerator 15 by air admitted through 73, with the products of combustion passing out through stack 74 and stack valve 75. Meanwhile the valve 37' or 46' or 52 may be closed to force all blow gases into the regenerator 15 when that is desired and when only a portion of these blow gases is passed therein in the valves 75 or 30' or 28' and 37' or 46' or 52 are so regulated as to effect the required division of flow through 15 and the other apparatus and out through stack valves 75 and 52. This is preferably done in starting up the apparatus to give the regenerator its initial heat and to then purge the regenerator of air but may be done thereafter if desired.

When the heat in the down run gases is relied on to heat the regenerator 15, the stack 74 and valve 75 may be dispensed with and a short purge run first made by passing steam through the regenerator, the said steam being admitted as at 71 to drive out the air therein.

With the fuel bed and apparatus at the desired temperature, air blasting is discontinued and all air and blow gas valves as 54, 23', 23a', 23b', 23c', 39, 52, 73 and 75 are closed.

When 15 has been first heated by blow gas, steam is admitted at 71 and admixed with a restricted amount of air and/or oxygen when desired through 72. The mixture passes through the heat absorbing material, is highly superheated thereby and passes thence to the generator fuel column through 28, (the valve 28' and passageway 30 and valve 30' being omitted) and then through 24a' to the fuel at level 24a. When, however, the openings at level 24a are too large to admit the steam to the fuel at the desired velocity, the valve 28' is used and closed and the steam is passed through 27 into the fuel at level 24.

In either instance the steam bypasses the lower hot section of the generator thereby avoiding or reducing the cooling action of the steam and its decomposition on the underlying fuel and slag.

The superheated steam in contact with the hot fuel is decomposed into hydrogen and carbon monoxide mostly and passes up through the fuel and around the carbonizing chamber 21 through 37, 38, and is additionally heated in 40. In entering 43, liquid hydrocarbons are sprayed into the descending gas stream through 44. The highly heated blue gas with the radiant heat from adjacent refractory material heats the hydrocarbon particles to the desired temperature for cracking the same and forming stable hydrocarbon gases of the required density and heating value. The carburetted gas passes on through 41 and 41a and 57, 58 and heats the material 41a in passing therethrough and passes out through 59 to such other apparatus as desired or through 60 to a condenser or waste heat boiler 16.

When it is desired to carburet the gas under lower absolute pressures, a vacuum pump 17 is provided with which the regenerator 15, generator 10, and carburetter 11 may be operated at substantially lower pressures. This reduced

pressure may be used in the carburetter only with the valve 31' used to restrict the flow from the generator to the carburetter.

When the up run has continued for a sufficient time, the steam inlet 71 and air inlet 72, when used, are closed and the necessary closure made in the outlet 58. Steam is then admitted through 65' and admixed with air as desired through 66' and passes upwardly through 41a, 41, 43, 40, receiving a preliminary superheat in 41a by the heat stored therein by the outgoing carburetted gas and a final high temperature superheat in 40. It passes thence to the generator and through the fuel in 20 and is mostly decomposed therein and out as at level 24a and passageway 28 to the regenerator 15 and the gas passing therethrough gives up most of its heat therein and passes out through 19' and 19 to such other apparatus as desired.

This down run gas leaves the fuel bed at a relatively high temperature and when desired may be carburetted by hydrocarbons sprayed in as at 70 or 70'. The heat in the gas being relied on to furnish the heat for cracking and gasifying the hydrocarbons. In this case, the heat in the gas may be intensified by heat stored in the regenerator by the combustion of blow gases in the regenerator as previously described. It is, however, preferable to use enough down run steam so the down run gas will give off the required amount of heat in regenerator 15 to superheat the up run steam to the desired temperature and at the same time reduce the temperature of the outgoing down run gas through 19' and 19 to a relatively low point.

When, however, the heat in the down run gas is more than sufficient for superheating the up run steam, this gas may be carburetted with hydrocarbons admitted at 70 as previously stated or 70' or some of the up run steam may be generated by water or works effluent sprayed in as at 70, in which case the steam admitted at 71 is superheated and striking the water mist introduced at 70 vaporizes it, and it all passes upward and is superheated before entering the generator. Water or works effluent may be similarly vaporized in the carburetter during down runs through admission means as at 44 in a rising column of superheated steam.

The heavier hydrocarbons such as butane and propane may be introduced in the carburetter at 44 and in regenerator 15 at 70 when desired, the temperatures of the blue gas passing therethrough and refractory surfaces adjacent thereto being controlled to secure the desired cracking of these hydrocarbons with an avoidance of naphthalene and indene and styrene and other objectionable compounds as previously described. Optimum temperature conditions for the breaking down of these hydrocarbons and absorption of hydrogen from the blue gas for the formation of methane and/or other hydrocarbon gases in the maximum practicable quantities is thereby obtained. The production of the latter is of particular value for augmenting a natural gas supply at times of heavy demand or of failure in such supply.

When the lower passage 30 is used for drawing off the down run gases from the generator, these gases sweep the liquid slag into a pocket as 32 from which it is drawn off and 32 sealed in any desired manner. The valve 30' may be omitted when 30 is used to admit the up run steam which may be done when the hearth 31 is relatively free of liquid slag and the steam is highly super-

heated. It is however preferable with 30 used, to use the valve 30' closed during the up run period and force the steam through 21 at level 24 to prevent any chilling action on the lower section 5 of fuel and any liquid slag therein or on the hearth.

The operation with up and down runs and air blasting at different levels as desired is continued substantially as previously described. During 10 the run or gas making period the up and down run portions may be varied as desired.

As the operation progresses the fuel column is replenished as desired through charging inlet 22 with coke or bituminous fuel. With coke used, 15 the assembly 33 may be omitted, also the chamber 21 and inlet and connections therefor at level 24b, and the generator filled with fuel to any desired height with air blast levels suitably disposed throughout the height thereof.

20 Also, with coke used, the upper portion of the generator may be as shown in Fig. 2 with the blast gases drawn off through 81 and 82 with or without a valve therein as previously described, the passage 82 connecting into the carburetter 11. 25 In this case with assembly 33 omitted and newly charged fuel in the upper portion 80, part or all of the up run blue gas may be taken as desired through this fuel and off through offtake 36, the sensible heat thereof being used in preheating 30 the newly charged fuel.

With bituminous fuel used, the chambers 21 in Fig. 1 and 80 in Fig. 2 are used as carbonizing chambers. In Fig. 1, the chamber is heated by the blow and run gases passing around it, the 35 run gas that is passed through it and the superheated steam admixed with air admitted through 24b when desired as during the air blasting period admitted at 24b. The blue gas in passing up through 21 sweeps the volatile matter from the 40 fuel, enters the assembly at the bottom and passing the annular openings throughout its height, brings in and induces into the assembly the vapors and gases from the fuel at a temperature close to their distillation temperature and 45 under partial pressure conditions such that these pass through the assembly and out through 36 without condensation. A rapid rate of carbonization is thereby obtained and the tendency of the fuel to swell and form a plastic zone is thereby 50 reduced or avoided.

Carbonization is similarly effected in 80 in Fig. 2 except that the heat in the blue gas passing therethrough and/or steam and combustion of any air or oxygen admixed therewith is relied on 55 to supply the heat for carbonization.

The fuel temperature in the chamber 21 with steam admitted at 24b may be so controlled as to provide optimum conditions for the formation of ammonia which is drawn off with the gases 60 through offtake 36.

In making blue gas with up and down runs, the carburetter 11 is omitted and outlet 37, valve 37' being omitted, is directly connected into 46, the valve 46' being also omitted as well as the 65 superheated steam line 67, valve 68 and line 26.

In this case the steam superheater 12 is heated by the blow gases and the secondary combustion thereof by air admitted through 48.

70 The steam admitted therein at 65 with any air or oxygen admixed therewith through 66 is superheated and passes to the generator as before and the blue gas formed therefrom passes to the regenerator 15 as before.

The up run steam is admitted to regenerator 75 15 as before and the blue gas is passed through

the newly charged fuel as 21 in Fig. 1 or 80 in Fig. 2, and out through offtake 36 with the sensible heat thereof utilized in preheating and/or distilling the fuel therein as previously described.

In this case the sensible heat in the down run 5 gas is used as before in superheating and/or generating the up run steam, the sensible heat of the up run gas is used in preheating, distilling and/or carbonizing the newly charged fuel, the blow gas heat is used in superheating the down 10 run steam and preheating the air for blasting and in heating the carbonizing chamber when used as in Fig. 1.

15 In making carburetted water gas with all down runs the regenerator 15 is used as a carburetter, the carburetter 11 is omitted and passage 37 connected directly into 36 with valves 37' and 46' and piping 67, 68 and 26 omitted as previously described for making blue gas. The upstream connections to the generator are also 20 omitted. In this case the steam passes from the superheater 12 as before for blue gas and the down run gas is carburetted in 15 by hydrocarbons admitted at 70 or 70', the sensible heat 25 in the gas being relied on to crack and gasify the hydrocarbons. The resulting gases are drawn off through 19' and seal separator 19 or waste heat boiler or condenser such as shown at 16 equipped with a vacuum pump 17 for lowering the absolute pressures during the carburetting process as previously described.

30 With bituminous fuel used in this case, superheated steam and air or oxygen admixed therewith as desired may be passed up through the carbonizing chamber for carbonizing and carrying off vapors and gases as previously described.

35 With up runs only used, the regenerator 15 is dispensed with and with carburetted water gas, the valve 37' is used or omitted as previously 40 described. The valve 46' is used and secondary combustion of blow gases effected in the carburetter 11 as before and completed in 49 by air admitted through 48.

45 The set is air blasted as before and during the running period the steam and any air admixed therewith as desired is superheated in the superheater 12 and passes thence to the lower portion of the generator through 68, 67, 26 at level 24 and is also admitted for carbonization 50 as previously described at level 24b. The up run gases are passed through the carbonizing or preheating chambers in any desired proportion and drawn off through 36, the remainder to the carburetter and drawn off as previously described 55 through a seal separator or waste heat boiler or condenser and/or vacuum pump.

With up runs only made in manufacturing blue gas the carburetter is dispensed with and all of the gas passed through newly charged fuel 60 and drawn off through the upper offtake.

When it is desired to make a high hydrogen content blue gas and/or carburetted water gas from bituminous fuel the down run operation 65 is varied as follows: steam is passed downwardly through the newly charged fuel in chamber 21, Fig. 1, or in chamber 80 in Fig. 2 the steam being admitted above the fuel as at 24d in Fig. 1. This steam is preferably superheated and supplied to 24d from either 42 or 68 with the valve 37' or 46' closed meanwhile. The assembly 33 may be modified or dispensed with as desired. The steam and distillation gases then pass downwardly through the incandescent fuel in the 70 generator and the hydrocarbon gases are cracked 75

in passing therethrough into hydrogen and carbon mostly, with the carbon therefrom and/or the carbon from the fuel and the steam forming water gas. The hydrogen and water gas then pass from the lower part of the generator as previously described. In this case when a maximum production of hydrogen is desired preferably the down run steam only is passed through the newly charged fuel so all the hydrocarbon gases and vapors therefrom may be substantially reduced to carbon and hydrogen.

The hydrogen content of the gases may also be increased by spraying in liquid hydrocarbons over the fire as at 24c admixed with steam when desired and preferably into a current of highly superheated steam entering the generator through 37. The liquid hydrocarbon is then cracked into hydrogen and carbon with the carbon therefrom in contact with the steam at high temperatures forming water gas mostly. These down run gases are drawn off from the lower part of the generator as previously described.

In Fig. 3 is shown a modified method for drawing off liquid slag from the base of the generator. The slag level in the spout at 86 is sufficiently higher than in the generator at 85 to seal off the gases at the higher pressure in the generator. As the slag accumulates in the generator the slag overflows at 86. A heating means for keeping the slag liquid in the spout is indicated by a gas burner 87. At 88 is shown a plug which may be removed for draining out the slag as in shutting down.

In Fig. 4 is shown another method for drawing off liquid metal at opening 91 and slag at 92 separately as for example when iron ore or other metal-containing material is used as a flux, the molten metal being indicated by 90 and the liquid slag at 85.

The pipe 93 in Fig. 4 may be used for admitting a fluxing material in the air tuyères which may be blown in with the blasting air. Also gas or oxygen may be admitted through 93 and mixed with the blasting air as previously described.

In cracking methane and/or natural or other hydrocarbon gases, the air blasting is carried on as described, and said gases, admixed with steam when desired, are passed through the regenerators and incandescent fuel bed in the same manner as described for steam. The thick high temperature fuel bed cracks the gas into hydrogen and carbon mostly, with the hydrogen gas and any water gas formed therewith drawn off as previously described for water gas.

From the preceding description it will be seen that the invention provides highly efficient methods for removing ash and clinker forming material as liquid slag with up runs only, down runs only, or combination up and down runs with the sensible heat of the blue gas and/or carburetted water gas and sensible and potential heat in the blow gas utilized in superheating and/or generating steam for cracking and gasifying hydrocarbons, preheating air, distilling and/or carbonizing and/or preheating fuel; for increasing the hydrogen content of such gases and for the production of hydrogen from natural gas and other hydrocarbon, in improved heat cycles so that the gas apparatus may be operated at high capacities and efficiencies under optimum conditions.

Having described my invention, I claim:

1. The herein described improvement in the method of manufacturing water gas which includes: air blasting a generator fuel bed to incandescence by air admitted in the lower portion thereof; alternately with the air blasting, admitting steam and a restricted amount of air simultaneously and admixed to the fuel column in the lower portion thereof above the air blast level for an up run and, alternately thereof, steam to the upper portion of the fuel column for a down run; drawing off the up run gases from the upper portion of the fuel column; drawing off the gas from the lower portion of the column; admitting air to the lower portion of the fuel bed during the up run of steam and in an amount restricted such that the heat liberated by the combustion thereof is less than the heat absorbed in the decomposition of the up run steam, and discharging ash and clinker-forming material as liquid slag.

2. The herein described improvement in the method of manufacturing water gas which includes: air blasting to incandescence, the lower portion of a generator fuel bed having an upper newly charged fuel portion; passing the blow gases thereby produced from the upper portion of said incandescent portion of the fuel bed; alternately with the air blasting, admitting steam to the fuel column in the lower portion thereof above the air blast level and causing the gas thereby produced to pass from the upper portion of said incandescent portion of the fuel bed through said newly charged fuel portion and, alternately of said steam admission, admitting steam to the upper portion of the incandescent portion of the fuel column, passing the same downwardly and drawing off the gas thereby produced from the lower portion of the column; and discharging ash and clinker-forming material as liquid slag.

3. The herein described improvement in the manufacture of water gas which includes: air blasting a column of fuel to incandescence in the lower portion thereof; alternately with the air blasting, admitting steam to the fuel column alternately in the lower portion thereof above the air blast level and drawing off the gas thereby produced from the upper portion of the fuel column, and to the upper portion of the fuel column; drawing off the gas thereby produced from the lower portion of the column and causing said gas to pass through a regenerator for heating the same, injecting hydrocarbons into said gas for carburetting the same as it passes through said regenerator, and superheating the steam admitted to the lower portion of the fuel column in said generator and discharging ash and clinker-forming material as liquid slag.

4. The herein described improved in the manufacture of water gas which includes: air blasting a column of fuel to incandescence in the lower portion thereof; alternately with the air blasting, admitting steam to the fuel column alternately in the lower portion thereof above the air blast level and drawing off the gas thereby produced from the upper portion of the fuel column, and to the upper portion of the fuel column; drawing off the gas thereby produced from the lower portion of the column and causing said gas to pass through a regenerator having upper and lower regenerative zones for heating the same, and generating and superheating the steam admitted to the lower portion of said generative fuel bed by admitting and superheating steam in said lower regenerative zone, admit-

ting water thereabove and vaporizing such water in the column of superheated steam rising from said lower regenerative zone, and causing the steam so formed and superheated to pass through and to be superheated in said upper regenerative zone, and discharging ash and clinker-forming material as liquid slag.

5. The herein described improvement in the method of manufacturing water gas which, when carried out in a generator having a slagging bottom, includes: air blasting a column of fuel to incandescence in the lower portion thereof;

alternately with the air blasting, generating water gas by admitting steam to the fuel column successively in the lower portion thereof above the slagging bottom and air blast level for an up run and then in the upper portion for a down 5 run; withdrawing the formed water gas from the up run from the upper portion of the fuel column and the formed water gas from the down run from the lower portion of the incandescent fuel; and discharging ash and clinker-forming 10 material as liquid slag.

HIRAM J. CARSON.
